INFLATABLE BALL FLIP AND CATCH TOY

Eugene R. Caporale, 225 Stephen St.,
North Bellmore, N.Y.

Filed June 16, 1964, Ser. No. 80,428

Term of patent 14 years

(Cl. D34—15)

FIG. 1 is a front elevation of the inflatable ball flip and catch toy embodying my new design,

FIG. 2 is a side view thereof, and

FIG. 3 is a top view.

I claim:

The ornamental design for an inflatable ball flip and catch toy, substantially as shown.
